UNITED STATES PATENT OFFICE.

EDWARD BROWN AND SAMUEL HERBERT MARTIN, OF TORONTO, ONTARIO, CANADA,
ASSIGNORS TO THE MARTIN CORRUGATED PAPER AND BOX COMPANY, LIMITED,
OF TORONTO, CANADA, A CORPORATION.

AUTOMATIC SHEARING-MACHINE.

1,009,028.

Specification of Letters Patent. Patented Nov. 14, 1911.

Application filed March 23, 1911. Serial No. 616,495.

To all whom it may concern:

Be it known that we, EDWARD BROWN and SAMUEL HERBERT MARTIN, both of the city of Toronto, in the county of York, in the 5 Province of Ontario, Canada, have invented certain new and useful Improvements in Automatic Shearing-Machines, of which the following is the specification.

Our invention relates to improvements in 10 automatic shearing machines and the object of the invention is to devise a machine of this class in which paper or cardboard as it passes through the machine may be cut off into desired lengths without stopping or 15 slowing the machine feed and it consists essentially of a feeding table provided with a ledger plate and a delivery table suitably supported, a shearing knife and means for imparting a combined downward and longitudinal 20 movement to the knife so as to impart to the knife a longitudinal draw, a gage device, a clutch operated by the gage device designed to be thrown in by the contact of the card with the gage thereby throwing 25 in the knife operating mechanism as hereinafter more particularly described by the following specification.

Figure 1, is a general perspective view of our device. Fig. 2, is a longitudinal section 30 through Fig. 1. Fig. 3, is a cross section.

In the drawings like letters of reference indicate corresponding parts in each figure.

A is the main frame provided with standards A' having vertical slots A².

35 B is a longitudinal ledger bar and B' is a ledger plate secured thereto.

D is a receiving table.

E is the delivery table having a central longitudinal slot E'.

40 A³ is a cross bar connecting the top standards A' A' together.

F and F' are links swung upon the cross bolts F² extending through the standards A' A' and the slots A².

45 G is a shearing knife provided with bearing brackets G' and G² to which the links F and F' are pivotally connected by the cross pins H and H'. It will be noticed on referring particularly to Fig. 3 of the drawings that the bracket G' is slightly lower than the bracket G² thereby imparting a slightly inclined set to the shearing knife in relation to the ledger plate B'.

I is a series of spiral tension springs

connecting the knife G with the cross bar 55 A³. The tension springs serve to counter-balance the weight of the knife on its return or upward movement.

J is the main driving shaft journaled in suitable bearings J' and provided with a 60 driving pulley J².

J³ is the operating arm of a clutch designed to throw the driving pulley J² into and out of engagement with the shaft J. We do not show the construction of this 65 clutch as any suitable form may be used for this purpose.

K is a crank wheel mounted upon the shaft J, and K' is the link connecting the crank pin K² of the crank wheel K to the 70 cross pin K³ extending through the end of the knife G.

L is a lever pivotally secured at one end to the main frame of the machine.

L' is a link connecting the opposite end 75 of the lever L with the clutch arm J³.

M is the main gage bar adjustably connected to the delivery table by set screws M'.

M² are lugs forming part of the gage bar and provided with holes M³. 80

M⁴ is a supplemental gage bar provided with end brackets M⁵ slidably supported on the edge of the table E.

M⁶ are stems extending rearwardly from the gage bar M⁴ through the hole M³ of the 85 main gage bar M.

M⁷ are compression springs surrounding the stems M⁶ downward between the lugs M² and the brackets M⁵.

M¹⁰ is a central depending socket forming 90 part of the supplemental gage bar M⁴.

N is a rod extending through the socket M¹⁰ at one end and adjustably secured therein by the set screw M'.

N² is a link connecting the opposite end 95 of the bar with the lever L.

Having described the principal parts involved in our device we will now describe the operation of the same. The card or paper is fed in a strip onto the receiving table from which it is fed by suitable means over the ledger plate onto the delivery table until the edge of the card strikes the gage bar M⁴ thereby compressing the springs M⁷ allowing the gage bar M⁴ to recede. This 100 movement of the gage bar M⁴ draws the bar N longitudinally and swings the lever L 105 on its fulcrum. This motion of the lever

L pulls over the clutch arm J³ thereby throwing in the clutch and connecting the pulley J² to the shaft J. The crank wheel K then forces the link K' and knife bar G longitudinally the links F and F' carrying the bar downwardly imparting to the knife a downward and longitudinal draw co-acting with the ledger plate to quickly sever the card. The continued motion of the crank wheel serves with the aid of the compression springs I to quickly withdraw the knife out of the path of the card thereby preventing the knife interfering with the continuous feed of the card or paper in the shearing machine.

From this description it will be seen that we have devised a very simple machine whereby card or paper may be cut into any desired lengths without stopping or slowing the feeding of the paper there into.

What we claim as our invention is,

1. In an automatic shearing machine, the combination with the ledger plate, of a swingably supported knife bar and means for imparting a longitudinal movement to the knife bar, of a delivery table, a gage device supported on the delivery table, a clutch arm and means for operating the clutch arm to throw in the knife operating mechanism by the contact of the card with the gage device, as and for the purpose specified.

2. In an automatic shearing machine, the

combination with the main driving shaft and the clutch arm designed to throw the same in and out of gear, of a delivery table, a gage device comprising a stationary bar adjustably secured to the table, a supplemental gage bar, compressible means between the supplemental gage bar and the stationary bar, and connecting means between the supplemental gage bar and the clutch arm, as and for the purpose specified.

3. In an automatic shearing machine, the combination with the main driving shaft and driving pulley, and a clutch arm for throwing the driving shaft into connection with the driving pulley, of a delivery table, a gage bar adjustably secured to the delivery table, a supplemental gage bar provided with stems extending slidably through the first mentioned gage bar, springs surrounding the stems and extending between the supplemental and first mentioned gage bars, a lever pivotally connected with the frame at one end, a link connecting the opposite end of the lever to the clutch arm, and a link bar connecting the supplemental gage bar to the lever, as and for the purpose specified.

EDWARD BROWN.

SAMUEL HERBERT MARTIN.
